UNITED STATES PATENT OFFICE.

CHARLES H. TRACY, OF BERKELEY, AND FRANK C. GOULD, OF ALAMEDA,
CALIFORNIA.

ATTACHMENT FOR LETTER-BOXES.

SPECIFICATION forming part of Letters Patent No. 702,510, dated June 17, 1902.

Application filed November 30, 1900. Serial No. 38,247. (No model.)

To all whom it may concern:

Be it known that we, CHARLES H. TRACY, residing at Berkeley, and FRANK C. GOULD, residing at Alameda, county of Alameda, State 5 of California, citizens of the United States, have invented certain new and useful Improvements in Attachments for Letter-Boxes; and we do hereby declare the following to be a full, clear, and exact description of the 10 same.

The object of the present invention is to provide a simple and inexpensive attachment for letter-boxes by means of which a disinfectant may be introduced into the said letter-box, so as to impregnate and disinfect the 15 mail-matter contained therein, thus permitting of the letters or mail-matter being thoroughly fumigated or disinfected directly within the letter-box without causing mutilation 20 of the letter or mail-matter, which is occasioned where the letter or mail-matter is cut or perforated in order to introduce the disinfecting material. By means of the herein-after-described attachment the mail-matter 25 is thoroughly disinfected prior to its removal from within the letter-box by the carrier and the spread of contagious diseases prevented, or at least liability thereof reduced to a minimum, which is a consideration in a thickly- 30 populated district or city.

In order to understand the invention, reference should be had to the accompanying sheet of drawings, wherein—

Figure 1 is a front view in elevation of an 35 ordinary letter-box with a disinfectant-holder secured thereto, the same being partly broken away; and Fig. 2 is a top plan view of the holder.

In the drawings the letter A is used to indicate an ordinary letter or mail box to which 40 the disinfectant chamber or holder is attached. The disinfectant chamber or holder A' may be attached to the letter-box at any suitable place. However, we prefer to attach 45 the same to the bottom of the box A, as by so doing it will be out of the way. When so placed, the upper edge of the holder or chamber A' bears against the bottom of the box, the shape of the holder or chamber being made to conform to that of the bottom of 50 the box. By means of a screw-bolt B passed

through the chamber or holder the same is attached to the letter box, said screw-bolt screwing into a screw-threaded central hole a in the bottom B' of the box. In order that a tight joint may be formed between the holder or chamber A' and the letter-box, there is interposed between the upper edge of the holder or chamber and bottom of the letter-box a packing or gasket a'. One side or end B² is 60 hinged to the holder or chamber. This hinged side or end is provided with a lock b, by means of which when closed it may be locked to the holder or chamber. By this means tampering with the interior of the holder is 65 provided against.

Within the holder or chamber A' is fitted the tray C, which tray serves to hold the disinfectant material. This tray may be composed of any suitable material, preferably 70 such as is not affected by the material placed thereon, and is slotted for a portion of its length, as shown, to enable the insertion of the same into the chamber A' without interference with its holding-screw.

Communication is established in the present case between the interior of the letter-box and the holder by means of a series of holes b' in the bottom of the letter-box. These 75 holes permit the vapor of the disinfectant to 80 enter the interior of the letter-box, so as to disinfect the mail-matter therein.

When it is desired to renew the disinfecting material, it is only required that the hinged side or end be unlocked and lowered, when 85 the tray C may be removed and the disinfectant material replenished.

It is obvious that the holder may be attached to any portion of the letter-box which will not interfere with the proper use thereof. Hence we do not wish to be understood as confining ourselves to the particular 90 described location for attachment of the same. It is also obvious that the holder may be formed integral with the letter-box.

Having thus described our invention, what we claim as new, and desire to secure protection in by Letters Patent, is—

1. In combination with a mail-box provided with suitable openings leading to the exterior 100 thereof, of a slotted tray adapted to hold disinfectant material adjacent said openings

outside the box, and a screw passing through the slot in the tray and engaging the box to hold the tray in place, substantially as described.

5 2. In combination with a mail-box provided with openings in its bottom, a holder, means for securing the holder to the bottom over the openings therein, means permitting access to the interior of the holder and a lock for said

10 means, substantially as described.

3. In combination with a mail-box provided with suitable openings in the body portion thereof, a holder, means for securing the holder to the surface of the body over the
15 openings therein, a removable tray in said holder, and means for locking the tray within the holder, substantially as described.

4. In combination with a mail-box provided with suitable openings in the body thereof, a
20 holder, a removable tray in said holder, and a screw passing through said holder from the outside thereof and engaging the box to secure the holder thereto, substantially as described.

5. In combination with a mail-box provided

with suitable openings in the body thereof,
25 a flanged holder, means for detachably securing the holder to the exterior of the box over the openings therein, a packing interposed between the surface of the box and the holder, and means for securing the holder to the box
30 and forcing the flanges of said holder against the packing, substantially as and for the purpose described.

6. In combination with a mail-box, a flanged holder adapted to receive disinfectant material, and means for detachably securing said holder upon the surface of the box, said box being provided with suitable inlets for fumes from the disinfectant material in the holder,
35 substantially as described.

40 In witness whereof we have hereunto set our hands.

CHARLES H. TRACY.
FRANK C. GOULD.
